SIGNAL STORAGE DEVICE OF THE MAGNETRON TYPE

Albert M. Skellett, Madison, N. J., assignor to National Union Electric Corporation, Hatboro, Pa., a corporation of Delaware

Application December 21, 1953, Serial No. 399,318

4 Claims. (Cl. 250—27)

This invention relates to signal storage systems and apparatus.

A principal object of the invention is to provide a novel form of signal storage system employing a magnetron as the storage device.

Another object is to provide a magnetron and associated circuits whereby the magnetron can be pulsed to two different persisting stable conditions.

A feature of the invention relates to a novel pulse-controlled keying system employing a simplified magnetron device and a novel combination of associated magnetic field producing elements.

Another feature relates to the combination of a magnetron tube of the two-element cathode and concentric anode type, having three magnetic field producing elements, one of which is arranged to be energized by an applied signal pulse to switch the magnetron to either of two different persisting stable conditions.

A further feature relates to an improved and simplified pulse-controlled magnetron keyer.

A still further feature relates to the novel organization, arrangement, and relative location and interconnection of parts which cooperate to provide an improved magnetron signal storage system.

Other features and advantages, not specifically enumerated will be apparent after a consideration of the following detailed descriptions and the appended claims.

In the drawing, which shows by way of example certain preferred embodiments:

Fig. 1 is a graph explanatory of the invention;

Fig. 2 is a perspective view of one form of device according to the invention;

Fig. 3 is a schematic wiring diagram of the device;

Fig. 4 is another view of the device of Fig. 2;

Fig. 5 shows a modification of the device;

Fig. 6 shows a portion of a typical impulse counting system embodying certain features of the invention;

Fig. 7 is a graph used in explaining the operation of Fig. 6.

I have discovered that a magnetron of the coaxial cathode and surrounding cylindrical anode kind can be made to have two stable persisting anode current conditions. I have also found that these two stable persisting conditions can be pulse-controlled by incorporating a plurality of magnetic field producing elements, one of which is a coil which can be connected to a source of electric pulses. Thus, referring to Fig. 1, there is shown in graph form the relation between the resultant magnetizing field acting on the electrons between the concentric cathode and anode, and the anode current conditions. When the resultant magnetic field has a value H_2 , the plate current assumes a persistent steady value at approximately zero. On the other hand, when the resultant magnetic field has a smaller value H_1 , the anode or plate current persists at an entirely different steady value. In accordance with the invention, these two stable persisting conditions are controlled by a momentary signal pulse which cooperates to trigger the

desired resultant magnetic field so as to determine which one of the persisting stable conditions is to exist.

In accordance with the invention, the magnetron tube is designed and is supplied with the necessary cathode and anode direct current potentials which, however, remain at their preset design values for both of the stable operating conditions. The switching from one condition to the other is controlled entirely by an input signal pulse which modifies and triggers the magnetic field from one value to the other, but without changing the applied potentials on either the cathode or anode. The invention, therefore, is clearly distinguishable from any magnetron system wherein the anode or plate current is keyed on or off by changing the bias or operating potentials of the magnetron electrodes.

Referring to Fig. 2, the device comprises an evacuated bulb 10 of glass or other similar non-magnetic material. Suitably mounted within the bulb is a linear, and preferably cylindrical, electron emitting cathode 11. Coaxially surrounding cathode 11 is a cylindrical plate or anode 12. Cathode 11 may be of any construction well known in the electron tube art, comprising, for example, a tubular cylindrical metal sleeve which can be raised to electron emitting temperature by a suitable heater element 13 which is schematically illustrated in Fig. 3, and which may be a filament mounted on the interior of, but electrically insulated from, the sleeve 11. Preferably a heater element 13 is of a type which is non-inductive or at least has negligible external magnetic field when connected to a suitable source of filament heating current. The external surface of sleeve 11 has a coating of electron emissive material of any kind well known in the electron tube art.

Respective lead-in members or wires are provided for the various tube elements, and are sealed for example through the base or header portion of bulb 10. Thus, wires 14 and 15 are connected to the ends of the cathode heater 13; the wire 16 is connected to the cathode sleeve 11; and the wire 17 is connected to the cylindrical plate 12 or anode 11. The bulb 10 with its electrodes is enclosed in a coil structure consisting, according to one embodiment, of three separate coil windings 18, 19, 20, to form a composite tubular assembly unit indicated in Fig. 2 by the numeral 21, so that this plural coil unit can be telescoped over the bulb 10 as shown. The three coils of the unit 21 can be wound in the form of superposed coil windings and the relations of these windings, so far as the directions of the coil turns, is schematically illustrated in Fig. 4 by the conventional dot and cross symbols. Merely for simplicity, these coils are shown in Fig. 4 as each being of a single layer type.

It will be understood, of course, that each coil is of the desired number of turns either in a single layer or in a multi layer. Each of the coils has a pair of individual supply leads; for example, the supply leads for the coil 18 are designated by the numerals 22, 23. The supply leads for the coil 19 are designated by the numerals 24, 25, and the supply leads for the coil 20 are designated by the numerals 26, 27.

The coil 18 is connected in series with the direct current anode supply source 28. The coil 19 is connected directly in circuit with the direct current supply source 28 so as to have a steady direct current flowing therethrough. The coil 20 is connected to any suitable source 29 of signal pulses.

As a result of the coaxial arrangement of the coil windings and the similar coaxial relation of the electrodes 11 and 12, there is produced by each of the coils a magnetic field having a component located between the cathode and anode and extending parallel to the length of the cathode.

In accordance with one feature of the invention, the coil 19 is connected in series with the source 28 so as

to give to the said axial component of the magnetic field a value H_2 and at the same time to apply a direct current potential across the anode 12 and cathode 11, whereby the anode current remains at substantially zero value, as illustrated in Fig. 1. Under this condition, of course, the coil 18 is deenergized and it is assumed that the coil 20 is also deenergized. The plate or anode current of the tube 10, therefore, remains at this steady zero value, until a suitable input pulse is applied to the winding 20 of such a polarity as to produce an instantaneous field which opposes the steady field produced by coil 19. The instant that this occurs, plate current begins to flow between electrodes 12 and 11 and, therefore, this same current flows through winding 18.

Because of the opposed winding relations of the coils 18 and 19, when current does flow between the anode 12 and the cathode 11 through the tube and, therefore, through the coil 18, the magnetic field of the coil 18, considered axially along the cathode 11, is in a reverse direction to the corresponding field produced by coil 19 so that the field of one coil substantially cancels the field of the other, thus allowing the current between anode 12 and cathode 11 to flow steadily at the higher stable value represented in Fig. 1. This condition persists until a pulse of the opposite polarity is applied to winding 20 from source 29. At the instant of this pulse the field produced by winding 20 aids that produced by winding 19 so that plate current immediately ceases to flow between electrodes 12 and 11, and thus winding 18 immediately becomes deenergized. Therefore, the cessation of plate current persists even after the said pulse is applied to winding 20.

Instead of using an electromagnetic coil 19 to produce the steady component of magnetic field parallel to the cathode 11, this coil may be replaced by a permanent magnet 30 having pole pieces 31, 32, located adjacent opposite ends of the cathode external of the bulb 10. The orientation of the field of this permanent magnet is such that the permanent magnetic field therefrom extends parallel to the cathode 11 in the opposite direction to the field produced by coil 18. Thus, in the particular schematic arrangement of the windings shown in Fig. 5, the coil 18, when energized by the battery 28, as a result of plate current flow, produces a magnetic field in the direction of the dotted line arrow, whereas the permanent magnet 20 produces a field in the direction of the dot-dash line arrow.

Since the theory of operation of the simple coaxial cathode and cylindrical plate magnetron tube is well known, a detailed description thereof is not believed necessary herein.

It will be seen from the foregoing that the magnetron as described herein can be caused to assume two different steady plate current conductive states by applying a momentary pulse of the proper polarity to the winding 20. This enables the device to be used in any well known signal storage system, since the plate current condition of the tube 10 responds to the polarity of the pulse applied from source 29 and it persists even after the pulse is terminated.

Referring to Fig. 6, there is shown one typical storage or impulse counting system embodying a tube arrangement such as described hereinabove. In Fig. 6, the parts or elements which are the same as those of Figs. 1-5, bears the same designation numerals. Thus, there is shown in Fig. 6 a portion of a "ring" counting system of the generic Wynn-Williams type such as described for example in Proceedings of the Royal Society, A132, 295-310 (1931). Merely for simplicity, only three counting stages are shown, but a greater or less number may be employed. Each stage includes a magnetron tube 10₁, 10₂, 10₃, etc., each one of these tubes being similar to tube 10 of Figs. 2-5. Each magnetron has surrounding it in coaxial relation four magnetic field-producing windings, three of these windings, for example winding

18₁, 19₁, 20₁, corresponding respectively to the windings 18, 19 and 20 of Figs. 2, 3 and 4. These windings are designated by the same numeral as those of Figs. 2-4 but with appropriate numerical subscripts, thus the corresponding windings for the second stage are designated 18₂, 19₂, 20₂; and for the third stage 18₃, 19₃, 20₃. Each magnetron tube has a fourth winding 33₁, 33₂, 33₃, etc., wound coaxially with the remaining set of three windings. All of these fourth windings are connected in parallel to a line 34 over which are received the impulses to be counted.

The arrangement of the circuit connections is such that when one tube, for example tube 10₁ is plate current conductive at its higher stable condition as represented by the stable state #2 (Fig. 7) the next succeeding tube, namely tube 10₂, is in its lower state #1, but is primed ready to be shifted to the higher stable state when the next impulse to be counted is received over line 34. Coincident with the priming of said next succeeding tube, the tube next preceding tube 10 is shifted to its lower stable condition. The priming pulse for any given magnetron is obtained from a change in the stable conducting state of the next preceding magnetron. Once a magnetron tube has been primed, the receipt of the next impulse from line 34 causes that particular primed tube to change from its lower stable state #1 to its higher stable state #2. In doing so, the next succeeding magnetron tube, for example tube 10₃, in the chain is then primed. The windings 33₁, 33₂, 33₃, etc., can be considered as the firing windings; that is, they change the associated magnetron from its primed condition to its upper stable fired condition. The windings 19₁, 19₂, 19₃, are the priming windings; the windings 18₁, 18₂, 18₃, are the locking or holding windings which are energized by the steady plate current flow of the associated magnetron when it is in its higher or #2 stable condition. The windings 20₁, 20₂, 20₃, are the "defiring" windings for restoring the associated tube to its lower stable and unprimed condition.

For purposes of explanation, let it be assumed that at the moment, tube 10₁ is in the conducting state at its higher stable value as represented by the flat or horizontal portion of the graph in Fig. 7. This means that under this condition the resultant magnetic field acting on the electrons between the linear cathode and the surrounding tubular anode of tube 10 has the value H₁. Tube 10₂, which has been meanwhile primed, has a resultant magnetic field represented by the value H₃, and tube 10₃, and, of course, all the succeeding similar tubes in the chain or ring have not as yet been primed and have a resultant field H₂. It will now be assumed that an impulse is received on the line 34 which energizes all the windings 33₁, 33₂, 33₃, etc. This impulse will have no effect on the electron discharge in tube 10, since its magnetic effect will be simply to move the line H₁ towards the left without changing the stable conductive state of tube 10₁. For tube 10₂, however, the energization of winding 33₂ will cause the effective magnetic field to move from value H₃ to H₄ and tube 10₂ will thus be energized or fired, that is, the electrons will flow from the cathode to the anode. At the instant that this happens, a pulse of current flows through the primary winding 35₂ of transformer 36₂. The secondary of this transformer is connected in circuit with the "defiring" winding 20₁ of tube 10₁. As a result of this momentary energization of winding 20₁, the effective magnetic field acting on tube 10₁ will change from value H₁ to approximately H₃. Immediately that this happens, the field from the holding or locking winding 18₁ disappears and the field that is left when the pulse passes through zero is equal to H₂, thus the tube 10₁ is defired while the tube 10₂ is fired and the tube 10₃ is primed. A rectifier 37₂ is provided across the secondary winding 38₂ of transformer 36₂ to prevent a kickback of this pulse which might otherwise initiate discharge again in tube 10₁.

The discharge has thus been transferred under control of the received impulse from tube #1 to tube #2, and the discharge current flowing through coil 19₂, 19₃ of tube 10₃, primes the tube 10₃ so that it will be ready to be fired in response to the next received impulse over line 34.

It will be understood that each of the windings 19₁, 19₂, 19₃ is connected to the primary windings of a corresponding transformer similar to transformer 36₂ and the corresponding elements of these transformers and the associated rectifiers are designated by the same numeral with the appropriate subscript. In order to complete the ring, the last stage in the counting ring is connected back to the first stage. For example, if the ring were a three-stage counting ring, the back connection from the third stage to the first stage will be made by connecting the conductors A—A', B, and C—C' from stage #3, back to the corresponding conductors A—A', B, C—C' of the first stage.

From the foregoing description it will be seen that, depending upon the number of impulses received, one and only one of the corresponding magnetrons will be in its fired or upper stable conductive operating state. For example, if three impulses have been received only magnetron 10₃ is in this upper stable conductive state, thus providing the equivalent to a storage of the numeral 3.

While one particular system has been described for using the double stable magnetron conducting tube, it may be used in other similar systems wherein the two stable conditions are to be selectively controlled by applied signal pulses.

Various changes and modifications may be made in the disclosed embodiments without departing from the spirit and scope of the invention.

What is claimed is:

1. An impulse storage system, comprising at least three magnetron tubes of the concentric anode-cathode kind, magnetic field-producing means for each tube to selectively shift each tube from a low stable anode-cathode current condition to a higher anode-cathode current condition in response to successive received impulses to be stored, each tube having a priming winding, a holding winding, a firing winding, and a defiring winding, means connecting all the firing windings to an impulse receiving line, means connecting the holding winding of the first tube in series with the priming winding of the second tube, means connecting the priming winding of the third tube with the defiring winding of the first tube whereby in response to each successive impulse from said line only a corresponding one of said tubes is shifted to its higher stable current condition while simultaneously priming the next succeeding tube and defiring the next preceding tube.

2. An impulse storage system, comprising a chain of magnetron tubes each arranged to selectively assume a low and high stable anode-cathode current condition under control of a composite coaxial magnetic field, means to set up said field including a set of four coaxial windings for each tube, one winding being a priming winding, another a holding winding, another a firing winding, and another a defiring winding, means connecting the priming winding of each tube in series with the holding winding of a preceding tube, means coupling the defiring winding of each tube with the primary winding of the second succeeding tube, a common impulse supply circuit connected to the firing winding of each tube,

5 said windings producing a composite magnetic field whereby in response to successive received impulses applied to said firing windings each tube is successively shifted from its low stable current condition to its high stable current condition while the next preceding tube is fired and the next succeeding tube is primed.

3. An impulse counting system, comprising a series of chain connected magnetron tubes each having a set of magnetic windings, comprising a priming winding, a 10 firing winding, a holding winding, a defiring winding for selectively shifting each tube in succession from one 15 stable anode-cathode current condition to another stable anode-cathode current condition and for holding it in said other stable condition after the cessation of a received impulse to be counted, means connecting the firing windings to an impulse receiving line, means connecting the holding winding of each tube with the priming winding of the next succeeding tube, means including said line to energize all said firing windings simultaneously by 20 each successively received impulse whereby each tube in succession is shifted to a high stable current condition while the preceding tube is shifted to a low stable current condition and the succeeding tube is primed ready to be shifted to its high stable current condition in response to the next received impulse, means to derive a defiring pulse from the shift of one tube to a higher stable condition, and means to apply said defiring pulse to the defiring winding of the next preceding tube.

4. An impulse storage system, comprising at least 30 three magnetron tubes of the concentric cathode-anode kind, each tube having four separate field-producing means each in magnetic field reacting relation with the space between the cathode and anode of the respective magnetron tube, the first of said means being a winding 35 arranged for continuous energization from a source of direct current for normally maintaining the tube at substantially cathode-anode space current cut-off, the second of said means being a winding arranged for connection in series with the anode-cathode and energized by the 40 space current flow therebetween, the third of said means being a winding for connection to a source of impulses for energizing said third means to produce a magnetic field which opposes the magnetic field produced by the first means and thereby to prime the tube to a lower stable state of space current flow, the fourth means being a winding arranged to assist the third means to fire the space current flow to a higher stable state, circuit connections connecting the fourth means of the third tube to an 45 impulse producing circuit for producing a de-firing impulse derived from the shifting of the space current of the second tube from its lower stable value to its higher fired value, and additional circuit connections for applying the said de-firing impulse to the third means of the first tube to restore said first tube to a de-fired space 50 current stable condition.
